Specification for Design.

Patented July 22, 1913.

Application filed February 5, 1913. Serial No. 746,388. Term of patent 14 years.

To all whom it may concern:

Be it known that I, EDGAR MOTT BOTTOME, a citizen of the United States, and residing at Moundsville, in the county of Marshall and State of West Virginia, have invented a certain new, original, and ornamental Design for a Glass Vessel, Figures 1 and 2 of the accompanying drawings being elevations of a glass vessel, illustrating different portions of the superficial ornamentation applied thereto.

No novelty is claimed herein for the shape of the vessel.

I claim:

The ornamental design for a glass vessel, as shown.

EDGAR MOTT BOTTOME.
